(57) **CLAIM**

The ornamental design for a tool bag, as shown and described.

DESCRIPTION

FIG. 1 is a perspective view of a tool bag showing my new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the bag of FIG. 1 in a first opened configuration;

FIG. 9 is a rear elevational view of the bag in the first opened configuration of FIG. 8;

FIG. 10 is a front elevational view of the bag in the first opened configuration of FIG. 8;

FIG. 11 is a left side elevational view of the bag in the first opened configuration of FIG. 8;

FIG. 12 is a right side elevational view of the bag in the first opened configuration of FIG. 8;

FIG. 13 is a top plan view of the bag in the first opened configuration of FIG. 8;

FIG. 14 is a bottom plan view of the bag in the first opened configuration of FIG. 8; and,

FIG. 15 is a perspective view of the bag of FIG. 1 in a second opened configuration.

The broken lines, including those representing the zippers shown herein are for illustrative purposes only and form no part of the claimed design.
